UNITED STATES PATENT OFFICE.

GEORGE A. LUCAS, OF SOUTH HANOVER, MASSACHUSETTS.

TROWEL.

SPECIFICATION forming part of Letters Patent No. 684,576, dated October 15, 1901.

Application filed February 9, 1901. Serial No. 46,630. (No model.)

To all whom it may concern:

Be it known that I, GEORGE A. LUCAS, a citizen of the United States, residing at South Hanover, in the county of Plymouth and State 5 of Massachusetts, have invented certain new and useful Improvements in Trowels; and I do hereby declare the following to be a full, clear, and exact description of the invention, such as will enable others skilled in the art to 10 which it appertains to make and use the same.

This invention relates to trowels; and it consists in the novel construction and combination of parts hereinafter fully described and claimed.

15 In the drawings, Figure 1 is a side view of the trowel. Fig. 2 is an end view. Fig. 3 is a plan view of the catch mechanism. Fig. 4 is a cross-section taken on the line *x x* in Fig. 3.

20 This trowel is specially adapted for smoothing the plaster in the corners of rooms.

A represents two plates, which are set at an angle and are connected together by a hinge *a'*, so that no portion of the hinge projects beyond their outer surfaces.

25 B represents arms which are pivoted together and to handle-bars *b* by pivots *b'*. These arms are also pivoted to lugs *c* on the plates *A* by pins *c'*. These arms have plates *d* around their pivots *b'*, which are provided with holes for the locking-rods *d'*.

30 C is the handle, which is secured between the two handle-bars *b*. When the locking-rods are retracted, the arms may be turned on their pivots *b'*, so that the plates *A* can be set at any angle to suit the corner of the room; but when the locking-rods are not retracted the handle, handle-bars, arms, and plates are all secured together rigidly.

35 D is a guide-cylinder secured to bars *g*, the outer ends *g'* of which are bent downward and also assist in supporting the locking-rods and the pivots *b'*. The outer ends of the bars *g* are secured to the handle-bars *b* in any approved manner. The locking-rods are 40 retractile and are provided with catch mechanism of approved construction.

45 E is a shaft journaled in the cylinder *D* and provided with a cross-bar *e* inside it.

50 F is a knob for turning the shaft *E*, secured on its projecting end above the cylinder.

Two pins *f* project from the end portions of the cross-bar *e* through slots in the bottom of the cylinder, and the locking-rods *d'* are pivoted to these pins.

55

G represents springs inside the cylinder which normally hold the locking-rods in engagement with the plates *d*, so that the plates *A* cannot turn on their pivot. The locking-rods are retracted by turning the knob *F*, 60 and when retracted the plates *A* can be set at various angles to suit the corners of the room.

What I claim is—

1. In a trowel, the combination, with two 65 hinged plates, of a handle, handle-bars supporting the handle, arms pivoted to the handle-bars and to the said plates, and rods projecting through holes in the overlapping portions of the said handle-bars and arms and operating to lock the said plates at various angles, substantially as set forth.

2. In a trowel, the combination, with two 70 hinged plates, of a handle, handle-bars supporting the handle, arms pivoted to the handle-bars and to the said plates, locking-rods 75 engaging with holes in the upper end portions of the said arms, and catch mechanism for operating the said locking-rods supported by the handle-bars under the handle, substantially as set forth.

3. In a trowel, the combination, with two 80 hinged plates, of a handle, handle-bars supporting the handle, arms pivoted to the handle-bars and to the said plates, a guide-cylinder, 85 bars securing the guide-cylinder to the handle-bars under the handle, a shaft journaled in the said cylinder and provided with an operating-knob, a cross-bar secured on the said shaft inside the cylinder and provided 90 with projecting pins, locking-rods pivoted to the said pins and engaging with holes in the upper ends of the said arms, and springs for holding the locking-rods in engagement with the said arms, substantially as set forth. 95

In testimony whereof I affix my signature in presence of two witnesses.

GEORGE A. LUCAS.

Witnesses:

ALICE J. MURRAY,
FREDERICK K. DAGGETT.
